UNITED STATES PATENT OFFICE

GEORGE E. LAND, OF PITTSBURGH, PENNSYLVANIA, ASSIGNOR, BY MESNE ASSIGNMENTS, TO MARY HAINES MARKS, OF SEWICKLEY, PENNSYLVANIA

PLASTER BASE

Application filed May 1, 1929. Serial No. 359,481.

My invention relates to plaster bases and more particularly to unitarily transportable bases.

Efforts have heretofore been made to apply different forms of smooth surfaced composition wall board to building timbers and apply plaster or the like thereto. Difficulty is experienced in securing a lasting bond between the composition board and the plaster applied thereto.

Where attempts have been made to use any one of the different forms of expanded metal or metal screening having relatively large meshes for supporting plaster, difficulty has been experienced in supporting the plaster or the like while in a semi-plastic state on the metal lathing or screening. In some constructions a backing sheet has been placed behind metal lath or screening for supporting the semi-plastic material until it hardens. In such constructions it has heretofore been customary to provide spacing strips between the composition board and the framing timbers. Thereafter the composition board is nailed to the spacing strips after which the metallic lath or screening is usually fastened to the composition board. Each of these operations is costly and it is difficult to secure uniformity of spacing and application of the different parts of the base to the framing timbers unless especially skilled workmen are employed.

I provide a plaster base in the form of readily transportable sheets comprising a backing sheet having corrugations formed therein which serve to space the sheet from the framing timbers. A metallic lath or screening is attached to the backing. For securing the metal lath or screening to the backing, securing means, one form of which is staples, are utilized which are positioned to not only secure the metallic lath or screening to the backing, but also to preserve the corrugations in the backing itself. Sheets so prepared can be transported to a building site and applied directly to framing timbers with but a single fastening operation.

The accompanying drawings illustrate certain present preferred embodiments of the invention in which

Figure 1 is a broken elevational view of a

body of plaster and a plaster base applied to framing timbers;

Figure 2 is a sectional view thereof taken substantially along the section line II—II of Figure 1; and

Figures 3 to 8 inclusive are views illustrating several forms of fastening devices applied to backing sheets.

Referring to Figures 1 and 2, a plaster base comprises a backing sheet 2 having corrugations 4 formed therein, a fabric 5 for supporting a body 6 of plaster or the like, and securing means, here illustrated in the form of staples or wires 7, to secure the fabric 5 to the backing sheet 2. The staples are preferably placed with their inturned ends 8 disposed at opposite sides of the corrugations 4 so that the staples not only secure the fabric in place, but also preserve the shape of the corrugations.

The sheet 2 serves to support plaster or the like when in a semi-plastic state. After the plaster or the like is hardened and the fabric is thoroughly imbedded therein, it is supported by the fabric and the backing sheet 78 has little work to perform. Accordingly, commercial stiffening or reinforcing paper, either chemically treated as by creosoting or the like, or plain, may be used for the backing sheet 2. The thickness of the paper is such that the corrugations 4 have considerable resistance to bending so that they serve to stiffen the plaster base and also to space the sheet 2 from framing timbers 9 a distance substantially equal to that of commercial 85 laths. By so spacing the backing sheet 2, the surface of the plaster is disposed at a distance from the timbers 9 which is the same distance as where plaster is applied to wooden lath. This construction eliminates the necessity for specially spacing the interior trim where my plaster base is used.

The base is secured to the timbers by nails 10 driven through the base, preferably in the corrugations 4, with their outer ends clinched over the fabric 5. Stiffening rods 11 may be laid in the corrugations 4, if desired.

While I have illustrated a fabric 5 in the form of screening, it is to be understood that different forms of metallic lath and expand-

ed metal may be substituted therefor without departing from the spirit of the invention or the scope of the appended claims.

By the term "plaster" as herein employed, I contemplate the use of any materials which are applied to a wall in a semi-plastic state and which harden into a solid condition.

Referring to Figure 3, a backing sheet 12 is provided with a rectangularly shaped depression 13 which serves as a spacing corrugation in the finished base. Staples or wires 15, one of which is illustrated, are driven into the sheet 12 on opposite sides of the depression 13 with their ends 16 clenched so that the staples 15 serve to preserve the shape of the corrugation 13 and prevent the side walls thereof spreading so that the effective depth of the corrugation is reduced.

In the modification shown in Figure 4, a backing sheet 17 is provided with a rectangular shaped depression 18, the shape of which is preserved by a staple or wire 19 which has its ends 20 clenched into the sheet on opposite sides of the depression 18. The intermediate portion of the staple 19 is bent to conform to the shape of the depression or corrugation. With this construction the upper surface of the corrugation is open, although the staples 19 preserve its shape.

Referring to Figure 5, a sheet 21 is provided with a corrugation 22 in which a staple 23 is driven through one of the side walls of the corrugation and the ends 24 of the staple are clenched over the outer surface of the opposite side wall.

In another form of the invention shown in Figure 6, a backing sheet 25 is provided with a V-shaped corrugation 26, the shape of which is reinforced by a staple or wire 27 lying externally of the outer surface of the corrugation. The ends 28 of the staple extend through the sheet 25 and are clenched over the opposite surface of the sheet.

Referring to Figure 7, a sheet 29 is provided with a rectangularly shaped corrugation 30 which is supported by an external staple or wire 31, the ends 32 of which extend through the sheet 29 and are clenched over the opposite surface.

In Figure 8, I have illustrated a sheet 33 having a V-shaped depression or corrugation 34 formed therein, the shape of which is preserved by a staple 5 of greater height than the staple 7 shown in Figure 2. The high staple 5 is used to span a stiffening rod 36 of considerable diameter when such is placed in the corrugation 34 and also to secure a fabric 37 in place. In addition the high staple permits a greater quantity of plaster to be inserted between the fabric and backing.

It is to be understood that the securing device shown in Figures 3, 4 and 6 to 8, inclusive, may be used to preserve the shape of a corrugation and may also be used to secure a fabric layer to the backing in a manner

corresponding to that shown in Figures 1 and 2.

While I have shown and described certain present preferred embodiments of the invention, it is to be understood that it may be otherwise embodied within the spirit of the invention and the scope of the appended claims.

I claim:—

1. A plaster base comprising a paper backing sheet having a self-sustaining corrugation formed therein, a fabric overlying said backing sheet and a plurality of individual members for both securing the fabric to the backing sheet and simultaneously preserving the width of the trough of said corrugation. 75

2. A plaster base comprising a paper backing sheet having a self-sustaining corrugation formed therein, a fabric overlying said backing sheet and stiffeners for securing the fabric to the backing sheet and simultaneously additionally sustaining the shape of said corrugation. 85

3. A base for plaster comprising a paper backing sheet having a plurality of self-sustaining stiffening and spacing corrugations formed therein, a sheet of fabric applied thereto and means for securing the fabric to the backing sheet at said corrugations whereby the securing means serves to strengthen the corrugations. 95

4. A base for plaster comprising a sheet of paper backing material having self-sustaining corrugations formed therein, a sheet of fabric applied thereto, reinforcing means disposed in at least one of said corrugations and means for securing the fabric to the backing sheet in cooperation with said corrugations whereby the securing means serves to help preserve the shape of the corrugation and retain the reinforcing means in said corrugation. 100

5. A base for plaster comprising a flexible non-metallic sheet of backing material having corrugations formed therein, transverse backing-stiffening and plaster reinforcing members associated with said backing material, longitudinal backing-stiffening and plaster reinforcing members disposed in at least one of said corrugations, and means for securing the transverse members to the backing sheet in cooperation with said longitudinal members and said corrugations, whereby the securing means serves to preserve the shape of the corrugations and retain the longitudinal members in position in said corrugations. 110

6. A base for plaster comprising a flexible non-metallic sheet of backing material having corrugations formed therein, transverse backing-stiffening and plaster reinforcing members associated with said backing sheet, longitudinal backing-stiffening and plaster reinforcing members disposed in at least one 120

130

of said corrugations, and a reticulated metallic plaster reinforcing member disposed between said transverse and longitudinal members, all four members being secured together to form a unitary structure.

7. A base for plaster comprising a flexible non-metallic sheet of backing material having corrugations formed therein, transverse backing-stiffening and plaster reinforcing members associated therewith, and means for securing the transverse members to the backing sheet in cooperation with said corrugations, whereby the securing means serves to preserve the shape of the corrugations.

10 8. A base for plaster comprising a flexible non-metallic sheet of backing material having corrugations formed therein, a backing-stiffening and plaster reinforcing wire mesh covering the backing material, longitudinal backing-stiffening and plaster reinforcing members disposed in at least one of said corrugations, and means including individual staples for securing the wire screen to the backing material, in cooperation with said 20 longitudinal members, whereby the staples serve to help preserve the shape of the corrugations and retain the longitudinal members in said corrugations.

9. A plaster base comprising a flexible 30 backing having spaced, creased, self-sustaining corrugations forming stiffening ribs therein, a wire mesh overlying the paper backing on the side opposite the ribs and a plurality of spaced individual staples extending 35 across the troughs of the ribs, for both securing the fabric to the paper and maintaining the width of the trough.

10. A plaster base comprising a backing 40 sheet of paper having corrugations formed therein, said paper being of such stock that the corrugations are substantially self-supporting longitudinally, plaster reinforcing means extending across said corrugations, and staples for securing said means to the 45 paper backing, said reinforcing means and said staples cooperating to preserve constant the width of the corrugations.

In testimony whereof I have hereunto set
my hand.

GEORGE E. LAND.
